UNITED STATES PATENT OFFICE.

EDWARD D. PUTT, OF AKRON, OHIO, ASSIGNOR TO THE FIRESTONE TIRE AND RUBBER COMPANY, OF AKRON, OHIO, A CORPORATION OF OHIO.

STITCHER-FEEDING MECHANISM FOR TIRE-MAKING MACHINES.

Application filed July 10, 1920. Serial No. 395,219.

To all whom it may concern:

Be it known that I, EDWARD D. PUTT, a citizen of the United States, residing at Akron, in the county of Summit and State of Ohio, have invented certain new and useful Improvements in Stitcher-Feeding Mechanism for Tire-Making Machines, of which the following is a specification.

This invention relates to mechanism for feeding or advancing stitchers or spinning rollers of a tire making machine radially along the sides of a tire core in the application and laying of the fabric about the core during the building operation. It relates particularly to a device for automatically slowing up or retarding the radial advance of the stitchers while they are being fed over the bead of the tire. It also consists of the combination of the automatic retarding mechanism with means for changing the angle of the stitchers as they pass around the bead.

This stitcher feeding mechanism is an improvement on the feeding device shown in the application of William C. Stevens, Serial No. 256,429, filed October 1, 1918.

The device as specifically shown includes a two rack feed for the stitchers which racks mesh with differential pinions, the larger pinion feeding the stitchers forward until the bead is reached, whereupon the feeding action passes to the smaller pinion.

While described as such a combination of elements, the invention is not so limited but may comprise other means and mechanism for performing the same train of movements within the scope of this invention.

In the drawings:

Fig. 1 is a plan view of the stitcher mechanism.

Fig. 2 is a longitudinal section.

Fig. 3 is a front elevation.

Fig. 4 is a transverse section.

Fig. 5 is a bottom view of the stitcher feeding racks.

Figs. 6 and 7 are plan views of the stitchers just prior to the commencement of the spinning operation and at the bead line, respectively.

Fig. 8 is a detail of the racks.

Fig. 9 is a detail of the ratchet for resetting the racks.

Fig. 10 is an enlarged section through the pinions which operate the ratchets.

This invention relates to the device for advancing the stitchers or spinners over a core and forming the fabric about the body of the carcass and the bead.

The core is shown at 1 and the fabric at 2, the beads being designated by the numeral 3. The body or framework of the machine is shown at 4, from which is suspended by means of bolts 5 a box or casing 6 in which is located the stitcher carrying slide. The mechanism for operating the stitchers and much of the details will not be described in this application as my invention relates only to the differential speed device by which the retarded movement of the stitcher is obtained at the bead line, together with the means for changing the angle of the stitcher at the time the feed is retarded.

The stitchers, which are freely rotating disks 7 are mounted on the ends of angular levers or arms 8, pivotally mounted at 9 in the ends of levers 10, which are extended rearwardly, curved, and pivoted at 11 on arms 12. The last mentioned arms are connected to links 13 pivoted on a common stud 14, rising from a carriage 15, slidably mounted in guideways 16 formed in the lower plate 17 of the box or casing 6. On the upper side of the plate 17 and projecting over the carriage 15 to maintain it in the guideway 16 are secured cam plates 18. These cam plates are formed with guideways or slots 19 in which travel rollers 20 carried on the forward end of the arms 12, the cams being shaped so as to guide the arms 12 in a path which will cause the stitchers to follow the curvature of the core and the bead.

The arms 10 and 12 are pivoted at 11 and are yieldably held in parallel relation by springs 20 bearing against the outside of levers 10 and surrounding bolts 21, which are fastened in levers 12 and pass through the levers 10. Bolts 21 are provided with washers and nuts 22 which serve to adjustably regulate the tension of the springs, 100

whereby the arms 10 may yield slightly as in passing over splices. Set screws 23 serve to limit the approach of the arms.

The bell crank levers 8 are connected by links 24 to arms 25 pivoted on arms 10 at 26, the ends of arms 25 projecting in position to be struck by pins 27, secured on the casing, the arms overlying each other and the pins projecting in opposite directions 10 from the top and bottom of the casing. The pins are located at such a point that when the stitchers arrive at the bead line, the the levers 25 will be rocked and the stitchers 7 will be moved about the point 9 whereby 15 the angle of the stitcher is changed in passing around the bead. Springs 24, surrounding links 24 serve to hold the rollers 7 in their proper position and allow them to accommodate irregularities in the surface 20 of the core or fabric.

Power to drive the racks and advance the stitchers is derived from a pinion 28 which is carried on the end of an arm 29 carried on a shaft 30, supported in hangers 25 31 depending from the casing 6. An operating lever or handle 32 is secured to the shaft 30 and by movement of this lever the pinion 28 is thrown into or out of mesh with large gear 33 which operates the rack as 30 will be described later.

The gear 28 is secured on a shaft 34, the opposite end of which carries a pinion 35 in mesh with a gear 36 on the shaft 30, which is driven from any suitable source of power. A latch 37 is pivotally suspended 25 from an adjustable plate 38 and is formed with an angular slot 39 which receives a pin 40 on the lever 32. When in the position shown in Fig. 2 the pinion is out of mesh with the gear 33, but if the lever 32 is raised, the pinion will become enmeshed and the latch will drop so that the pin will move into the portion 41 of the slot. This will serve to hold the pinion in mesh until 40 the carriage has advanced to its forward limit whereupon a pin 42 on the carriage strikes the underside of the latch and raises it, releasing the pin and causing the pinion to clear the gear. The stitcher carrying carriage is then returned by a spring or counterweight to be described. To provide a yielding connection in the gearing which advances the stitchers, so that in case of meeting an obstruction the drive will slip and the 45 stitchers be saved, any suitable form of frictional connection may be provided. A convenient arrangement is shown at 43 in Fig. 3 in which a friction clutch designated by the numeral 43 is provided between the gear 35 and the shaft 34. This arrangement will save much valuable time and parts in the operation of the machine.

The large gear 33 is secured to a main shaft 44 mounted in bearings 45 and extending under the casing 6. Around the shaft

44 on one side of the center line is carried a sleeve 46, the outer end of which carries a pulley 47 connected by chain 48 with a return spring seated in a cylinder 49, the purpose of which is to return the stitchers 70 after the pinion 28 is disengaged.

The sleeve 46 carries one member 50 of a friction clutch (Fig. 3), the other member being designated by the numeral 51. The two members of the clutch are pressed together by a spring 52. Rotation is transmitted to the sleeve 46 through the friction clutch in sufficient force to advance the stitcher.

The sleeve 46 carries a pinion 53, and on the shaft 44 is carried a pinion 54, the latter being somewhat smaller than the former. To the shaft 44 is secured a collar or sleeve 55 on which are pivoted pawls 56 which engage ratchet 57 formed on the gear 54. 80

On the underside of the stitcher carriage 15 is formed a rack 58 with which the pinion 53 engages, and in the stitcher carriage is supported a sliding or floating rack 59 which engages the pinion 54. On the underside of the carriage is secured a pin 60 which limits the forward movement of the rack 59 with respect to rack 58, and a pin 61 on the rear of the rack engages an abutment 62 to limit the rearward movement 95 of rack 59.

A gear 63 on shaft 64 and in mesh with gear 53 may be connected by sprocket 65 and chain 66 to any suitable cushioning device, if desired, for breaking the force of 100 the return movement of the stitcher carriage.

The operation of the device will be briefly described. Assuming the core 1 to have the fabric applied thereto and ready to stitch, the stitcher carriage being in retracted position, the parts are in the positions shown in Fig. 6, in which it will be noted that the floating rack 59 is in contact with pin 60, the position being shown more clearly in 110 Fig. 8.

The lever 32 is now moved so that pinion 28 engages gear 33, the latch 37 dropping into position to lock the arm 32 in raised position. Rotation is transmitted through shaft 44, friction clutch 50 and 51, sleeve 46 to pinion 53 which, in mesh with rack 58, moves the carriage forward. At this point it will be noted that pinion 54 is 115 smaller than pinion 53, and as a result, the rack 58 which is advancing through the friction clutch is moving faster than rack 59 which is advancing through power transmitted directly from shaft 44, pawl and ratchet 56 and 57 and pinion 54. As a result, rack 58 catches up on rack 59 until pin 61 strikes the abutment 62. This point occurs just as the spinning roller reaches the bead line and just as the spinner is turning, as shown in Fig. 7. 120 125 130

As the pinion 54 is directly driven from shaft 44, the friction drive for the pinion 53 must give way and the two racks advance together moving at the speed given by ratchet 57. This action gives slow advance around the bead so that the spinning rolls may do their work properly at this point, and the advance continues until the pin 42 strikes latch 37, releasing the pinion 28 from driving position. The spring or weight returns the carriage to its original position.

On the backward movement of the carriage, the pawl 56 slips over the ratchet and the rack 59 is stationary until it is struck by pin 60, reassuming its starting position.

The slower advance of the stitchers is obtained, not only by the differential pinions 53 and 54, but by the turning movement of 20 the stitchers through the levers 25 and connected parts serving to move their active point backwardly.

It will be seen that a simple and effective mechanism is devised for the automatic retarding of the stitchers or spinning rolls at the bead line, and while the description has been detailed, changes in size or arrangement of parts or other details may be made without departing from the invention.

30 I claim

1. In a tire making machine, a carriage, shaping tools mounted thereon, means for advancing said carriage radially of the core, and automatically actuated means for reducing the speed of advance of the carriage when said tools reach the bead line of the tire.

2. In a tire making machine including a rotatable core, spinning rollers, means for advancing said spinning rollers radially of the core, and automatically actuated means for adjusting the angle of the spinning rollers as they engage the bead portions of the tire and simultaneously changing the speed of their advance independently of said adjustment.

3. In a tire making machine, a core, a radially moving carriage, stitchers carried on said carriage, a feeding device for said carriage comprising a fast and slow speed device and automatically actuated means for shifting from the fast speed to the slow speed at the time the stitchers reach the bead on the core.

4. In a tire making machine, a core, a carriage stitchers pivotally supported by said carriage, means for automatically changing the angle of the stitchers at the point where they reach the bead of the tire, means to move said carriage radially of the core, and change speed mechanism in said carriage moving means operative to retard the advance of the carriage when the stitchers reach the bead.

5. In a tire making machine, a core, a car-

riage, stitchers pivotally supported by said carriage, means for automatically changing the angle of the stitchers at the bead line, means to move said carriage radially of the core, change speed mechanism in said carriage moving means, and means to render said change speed mechanism operative automatically at the same time that the angle changing mechanism becomes operative.

6. In a tire making machine, a sliding carriage, stitchers supported on said carriage, a rotating shaft, variable speed gearing between said shaft and said carriage, and means for automatically shifting from high to low speed in said gearing.

7. In a tire making machine, a sliding carriage, stitchers supported on said carriage, a drive shaft adjacent said carriage, a large and small pinion driven by said shaft, connections from said gearing to said carriage to advance it at different speeds, and means for shifting the drive from one of said pinions to the other.

8. In a tire making machine, a sliding carriage, stitchers supported on said carriage, a drive shaft adjacent said carriage, a large and small pinion on said shaft, racks on said carriage meshing with said pinions, and means for shifting the driving of said carriage from one of said pinions and racks to the other pinion and rack.

9. In a tire making machine, a sliding carriage, stitchers supported on said carriage, a drive shaft adjacent said carriage, a large pinion and a small pinion on said shaft, said large pinion being frictionally driven from said shaft, a rack secured to said carriage meshing with said large pinion, and a floating rack on said carriage in mesh with the smaller pinion.

10. In a tire making machine, a sliding carriage, stitchers supported on said carriage, a drive shaft adjacent said carriage, a large pinion and a small pinion on said shaft, said large pinion being frictionally driven from said shaft, a rack secured to said carriage meshing with said large pinion, a floating rack on said carriage in mesh with the smaller pinion, and contact points for said racks.

11. In a tire making machine, a sliding carriage, stitchers supported on said carriage, a drive shaft adjacent said carriage, a large pinion frictionally driven from said shaft, a smaller pinion, ratchet connections between the smaller pinion and said shaft, a rack secured to said carriage meshing with said large pinion and a floating rack on said carriage in mesh with the smaller pinion.

12. In a tire making machine a sliding carriage, stitchers supported on said carriage, a drive shaft adjacent said carriage, a large pinion frictionally driven from said shaft, a smaller pinion, ratchet connections

1
between the smaller pinion and said shaft, a rack secured to said carriage meshing with said large pinion, a floating rack on said carriage in mesh with the smaller pinion, and 5 contact points for said racks.

13. In a tire making machine, a sliding carriage, stitchers supported on said carriage, a drive shaft adjacent said carriage, a large pinion frictionally driven from said 10 shaft, a smaller pinion, ratchet connections between the smaller pinion and said shaft, a rack secured to said carriage meshing with said large pinion, a floating rack on said carriage in mesh with the smaller pinion, 15 and means for returning said carriage upon completion of the stitching operation.

14. In a tire making machine, a sliding carriage, stitchers supported on said carriage, a drive shaft adjacent said carriage, 20 a large pinion frictionally driven from said shaft, a smaller pinion, ratchet connections between the smaller pinion and said shaft, a rack secured to said carriage meshing with said larger pinion, a floating rack on said 25 carriage in mesh with the smaller pinion, contact points for said racks, and means for returning said carriage upon completion of the stitching operation.

15. In a tire making machine, a sliding carriage, stitchers supported upon said carriage, a drive shaft adjacent said carriage, 30 means for driving said carriage from said

drive shaft comprising a friction transmission device, a second driving mechanism for said carriage from said shaft, said first 35 named driving mechanism becoming inactive through said friction device when the second drive mechanism comes into action.

16. In a tire making machine, a sliding carriage, stitchers supported upon said carriage, a drive shaft adjacent said carriage, means for driving said carriage at two rates of advance comprising a friction transmission device, a second driving mechanism arranged to operate said carriage in one direction only, said first named driving mechanism becoming inactive through said friction drive, when the second drive mechanism comes into action, and means for returning 45 the carriage at the end of the stitching operation.

17. In a tire making machine including a rotatable core, a support, a carriage mounted upon the support for reciprocatory movement with respect to the core, relatively adjustable stitchers upon the carriage, and a common driving mechanism adapted to reciprocate the carriage and adjust the stitchers, said mechanism being constructed for automatic operation to simultaneously 55 change the speed of movement of the carriage and effect the adjustment of said stitchers.

EDWARD D. PUTT.
